UNITED STATES PATENT OFFICE.

LINTON H. HARRISON, OF ABILENE, TEXAS.

RAIL TIE AND FASTENING MEANS.

Application filed October 3, 1928. Serial No. 309,972.

The present invention covers a structure which includes as one of its features an especially designed hollow metallic tie, and as another one of its features, efficient rail 5 clamping and retaining means.

The improved structure is distinguished as a mechanical achievement in this already well developed art, and it is characterized by such desirable features as economy, durability and strength, practicability in construction, and such other features as insure firm anchorage of the rails, and dependable performance of the rail clamping and fastening means.

Briefly described, the rail tie is of metal of appropriate gage, being channel-shaped in cross section with the ends of the channel open, and with a transversely disposed reinforcing and anchoring bar disposed at 10 the center of the tie and fastened to the side walls of the tie. Struck up from the web portion of the tie at points spaced inwardly from the ends are tongues which are bent to form abutment lips to take over the base 15 flange of the rail. Removable clamping elements are cooperable with these lips, whereby to facilitate track laying and to insure 20 maintenance of proper operating conditions.

In the drawings:

Figure 1 is a top plan view of an improved rail tie and fastening means constructed in accordance with the present invention.

Figure 2 is a longitudinal section taken approximately upon the plane of the line 35 2-2 of Fig. 1.

Figure 3 is a bottom plan view of Fig. 1.

Figure 4 is a transverse section taken approximately upon the plane of the line 40 4-4 of Fig. 1 looking in the direction of the arrows.

Referring now to the drawings by numerals it will be observed that the tie is generally designated by the reference numeral 5. As before intimated, it is in the form of an open ended metal channel which in the present instance, is provided at its center with a transversely disposed reinforcing bar 6 having laterally directed end 45 portions 7 riveted or otherwise fastened to the side walls of the tie. Incidentally, it is to be noted that one end of the bar is bent in one direction and the opposite end in an opposite direction so that the points of connection will not be directly opposite each 50 other. It is understood that this tie is

adapted to be placed upon the rail bed in an obvious manner and after the track is laid thereon, the engine is permitted to run over the track to force the tie into the bed. 60 This compresses the dirt and rocks between the side flanges and anchors the tie firmly. It is important to note that the open end permits access to be had for tamping additional material into the end for firm anchorage. Moreover, the reinforcing member 6 also becomes imbedded in the ground 65 and guards against slippage in a direction longitudinal to the tie.

As before indicated, tongues 8 are struck up from the web portion of the tie and they are bent in the shape shown in Figure 2 to conform to and properly engage the adjacent flange of the rail base. Incidentally the rail is designated at 9. Moreover, these 70 tongues are disposed at predetermined distance from each other, and they act as gages so as to insure a uniform spaced parallelism of the track rails when laid. This avoids 75 improper connection of the rails with the ties such as frequently happens when they are spiked to the ties. Thus, the tongues have the function of gages and abutments as well as retaining elements. It is of course 80 necessary to use separate clamps 10 in conjunction with the abutment lips, these 85 clamps being fastened in place by bolts as is customary.

An important feature to note is the utilization of a wear plate 12 which is interposed 90 between the base flange of the rail and the web portion of the tie. The ends of this wear plate are bent down as at 13 and engage the side flanges of the tie. The plate 12 extends across the opening which is formed 95 by bending out the metal to provide the struck out tongues. Hence, it reinforces an otherwise weakened spot and constitutes a closure for this opening.

In the foregoing description and drawings 100 it will be seen that I have evolved and produced a combination rail tie and fastening means especially suitable for the purposes intended. It is highly advantageous from the standpoint of commercial success and comparative utility. It is thought to be a structure which has been previously unequalled in the art and one which will supersede the present day antique wood tie and fastening spikes. In this respect it is practical and 110 modern.

It is thought however that by considering

the description in connection with the drawings persons skilled in the art to which the invention relates will be able to obtain a clear understanding of the same. Therefore 5 a more lengthy description is regarded unnecessary.

Minor changes in shape, size, and rearrangement of parts coming within the field of invention claimed may be resorted to if 10 desired.

I claim:

In a structure of the class described, in combination, a rail tie comprising an open-ended hollow body of channel-shaped cross 15 section having gaging and abutment form-

ing tongues struck out from its web portion, transversely disposed wear plates extending across said web portion and having downturned ends engaging the side flanges of said tie, said wear plate extending over the 20 opening adjacent said struck out tongues, track rails extending across the end portions of the ties and resting upon said wear plates, having one side in engagement with said gage and abutment tongue, and separable 25 clamps bolted to the web portion of the tie and engageable with the outer side of said rails.

In testimony whereof I affix my signature.

LINTON H. HARRISON.
